Weedshing Fairbanks
ATTORNEYS:

UNITED STATES PATENT OFFICE

EDWIN A. LEE, OF PHILADELPHIA, PENNSYLVANIA

FOLDING CONTAINER

Application filed April 29, 1929. Serial No. 358,778.

My invention relates to a new and useful folding container particularly adapted for packing, storing and displaying various goods such as stockings, linens, scarfs, 5 handkerchiefs and the like.

My invention further relates to a folding container of this character which is adapted to contain one or more units of the goods being displayed or stored and one wherein 10 said goods, in addition to being carefully packed, is nevertheless easily and readily accessible.

My invention further relates to a container wherein the character of the goods may be 15 ascertained visually without the necessity of opening or unfolding the container or in any way disturbing the goods packed therein.

To the above ends my invention consists 20 of a folding container formed of a unitary integral blank comprising a substantially rectangular main body portion, relatively short flaps integral with the short edges of 25 said body portion, a relatively narrow flap integral with one of the long sides of said body portion, and a relatively wide flap integral with the opposed long side of said body portion, said last mentioned flap being 30 of a size substantially equal to that of said main body portion.

My invention further relates to a folding container of this general character, the main body portion of which is provided with an aperture through which the goods contained 35 therein may be felt and seen without opening or unfolding said container.

My invention further consists of a folding container of the general character described 40 formed of a blank, the main body portion of which is spaced from the juxtaposed folding flaps by pairs of parallel scorings which impart to the container a depth or height predetermined by the distance between said parallel scorings thus rendering my novel container adaptable for storing, packing and 45 displaying one or more articles at will.

My invention further consists of a container of this general character wherein a thin transparent sheet is superimposed upon the apertured main body portion to protect 50 the goods contained therein and displayed

through said aperture from dust and moisture, and from being handled by the customers.

For the purpose of illustrating my invention I have shown in the accompanying drawings forms thereof which are at present preferred by me, since the same has been found in practice to give satisfactory and reliable results, although it is to be understood that the various instrumentalities of 55 which my invention consists can be variously arranged and organized and that my invention is not limited to the precise arrangement and organization of the instrumentalities as herein shown and described. 65

Figure 1, represents a top plan view of the blank from which my novel folding container is formed.

Figure 2, represents a longitudinal sectional view of a folding container formed 70 by folding the blank shown in Figure 1.

Figure 3, represents a transverse section of the same.

Figure 4, represents a section similar to that shown in Figure 3 illustrating a modified form of my invention. 75

Referring to the drawings in which like reference characters indicate like parts, 1 designates a blank from which my novel folding container is formed which comprises the 80 main body portion 2, the end flaps 3, the relatively narrow side flap 4 and the relatively wide side flap 5, the main body portion 2 is provided with the aperture 6 of any desired size or contour with the creases or 85 scorings 7 and 8 which permit of the folding of the end and side flaps 3, 4 and 5 respectively.

The flaps 3, 4 and 5 are further provided with the scorings or creases 9 which in conjunction with the scorings 7 and 8 form side walls 10 which impart height or depth to the box or container formed when the blank 1 shown in Figure 1 is folded into the position seen in Figures 2 and 3. 11, 12 and 13 designate units of goods such as folded stockings, handkerchiefs, scarfs or the like which are superimposed in their folded condition upon the main body portion 2 of the blank before the folding of the side and end flaps 3, 4 and 100 105

5. The stockings 11, 12 and 13 can be seen or can be felt through the bottom aperture 6 thereby eliminating the necessity of completely unfolding or opening the container.

5 In Figure 4 I have shown a modified form of my invention wherein I interpose a transparent flexible sheet 14, of tissue paper, wax paper or the like, between the main body portion 2 of the container 1 and the contiguous goods 13 so that the color of said goods 10 may be determined without the necessity of opening or unfolding the container and so that said stockings may be protected from the atmosphere. The transparent sheet 14 15 may if desired be permanently secured to the body portion in any suitable manner.

It is to be noted that in forming my novel container I first fold the end flaps 3 and 4 inwardly over the body portion 2, to protect the 20 goods 11, 12 and 13, then fold the wide flap 5 which is of substantially the same size as the main body portion 2 inwardly so that it forms a complete cover for the container.

When it is desired to display the goods contained in my novel folding container, it is merely necessary to swing the wide flap 5, outwardly to expose to view both the color and the quality of the goods. By this construction it is unnecessary to disturb the folding of the goods being displayed and considerable time is saved in the packing and unpacking of the goods.

It will also be seen that my novel container is considerably less expensive to produce than conventional boxes heretofore used which generally consist of a built up bottom body portion and a built up separate cover.

I am aware that the invention may be embodied in other specific forms without departing from the spirit or essential attributes 40 thereof, and I therefore desire the present embodiment to be considered in all respects as illustrative and not restrictive reference being had to the appended claims rather than to the foregoing description to indicate the scope of the invention.

Having thus described my invention what I claim as new and desire to secure by Letters Patent, is:—

50 1. A folding container of the character stated, formed of a blank comprising a substantially rectangular body portion having an inspection aperture in the body thereof, end flaps integral with said body portion, 55 there being pairs of parallel scorings near said body portion at the base of all the flaps to permit of folding the latter over said body portion to form a well defined compartment having side and end walls, a relatively narrow flap integral with one side of said body portion, there being a scoring in said body portion at the base of said narrow flap 60 to permit of folding of said narrow flap over said body portion, an imperforate flap opposite to said narrow flap and integral with the

side of said body portion and of substantially the same size as the latter, there being a scoring in said body portion at the base of said imperforate flap to permit of folding the latter over the former to form said compartment, the scorings in all said side and end flaps being parallel to and spaced from said scorings in said body portion so as to form said side and end walls imparting height to said container when said flaps are folded over said body portion.

2. A folding container of the character stated, formed of a blank comprising a substantially rectangular body portion having an inspection aperture therein, end flaps integral with said body portion there being scorings in said body portion at the base of said flaps to permit of folding the latter over said body portion, a relatively narrow flap integral with one side of said body portion, there being a scoring in said body portion at the base of said narrow flap to permit of folding of said narrow flap over said body portion, an imperforate flap opposite to said narrow flap integral with the side of said body portion and of substantially the same size as the latter, there being a scoring in said body portion at the base of said imperforate flap to permit of folding the latter over the former scorings, there being scorings in said side and end flaps parallel to and spaced from the scorings in said body portion so as to form side and end walls to impart height to said container and to form a well defined compartment when said flaps are folded over said body portion, and a transparent sheet superimposed upon said body portion, and positioned interiorly thereof to cover said inspection opening therein.
